UNITED STATES PATENT OFFICE

2,046,183

ROAD SLAB SIDE EDGE REENFORCER

Robert R. Robertson, Chicago, Ill., assignor to
The Translode Joint Company, Chicago, Ill., a
corporation of Illinois

Application December 3, 1934, Serial No. 755,696

1 Claim. (Cl. 94—31)

This invention relates to a concrete road construction wherein the upper or crown section of the road is supported on a road subgrade and wherein the crown section of the road is divided into slabs or sections by means of spaced transversely disposed expansion joints and contraction joints and by means of a longitudinally positioned center joint. One of the important features of the road construction is to provide the road slabs with reenforcing means which are imbedded in the lower outer edge portions of the slabs and, if desired or found necessary, similar reenforcing means may also be imbedded in the upper outer edges of the concrete slabs. The outer edge reenforcing means are provided for the purpose of protecting the outer sides of the concrete slabs adjacent the road shoulders to prevent chipping off or breaking away of the edges of the concrete slabs.

It is an object of this invention to provide a concrete road construction wherein the top section or crown of the road above the road subgrade, has imbedded therein expansion and contraction joints as well as a load transmission center joint for dividing the road into a plurality of adjacently positioned concrete slabs divided by the various joints, and to provide the outer lower and upper edges of the side walls of the slabs with reenforcing means to protect said edges and prevent breaking off of the same.

It is also an object of this invention to provide the outer side of concrete road slabs with reenforcing means to prevent breaking off of the slabs in cases where the sides of the road are not sufficiently backed up or protected by the road shoulders.

It is a further object of this invention to provide outer edge reenforcing means for concrete slabs, said reenforcing means consisting of protecting bars having anchoring members for holding the bars in position to protect the edges of the slabs.

It is furthermore an object of this invention to provide a concrete road construction in which the road slabs have all of the upper and lower edges thereof protected by means of road joint members on three of the sides of the slabs while the outer or fourth sides of the slabs have the edges thereof protected by reenforcing members provided with anchoring means for holding the members secured in place.

It is an important object of this invention to provide a concrete road construction wherein the various edges of the road slabs are protected against breakage by both road joint members

and reenforcing members imbedded between and in the various road slabs.

Other and further important objects of this invention will be apparent from the disclosures in the specification and the accompanying drawings.

The invention (in a preferred form) is illustrated in the drawings and hereinafter more fully described:

On the drawings:

Figure 1 is a fragmentary top plan view of a concrete road having a load transmission center joint imbedded longitudinally in the road and intercepted at spaced intervals by road expansion joints and contraction joints dividing the road into concrete slabs having the outer edges thereof protected by reenforcing means imbedded in the slabs adjacent the shoulders of the road.

Figure 2 is an enlarged fragmentary transverse section of the road taken on line II—II of Figure 1 showing the side forms of the road in position.

Figure 3 is a fragmentary vertical inner side view of a road slab side edge reenforcer, embodying the principles of this invention, and shown in position against the inner surface of a road side form.

Figure 4 is a fragmentary transverse vertical section through one side of a concrete road showing the outer side wall of a concrete slab having reenforcing means imbedded in the concrete to protect both the lower and upper side edges of the slab.

Figure 5 is a fragmentary vertical inner side view of the slab side edge reenforcing means of the type illustrated in Figure 4, showing the same positioned adjacent the inner side of a road side form.

Figure 6 is a fragmentary perspective view of a modified form of slab side edge reenforcer provided with a top flange and having the anchoring means struck inwardly from substantially the middle portion of the upright flange of the reenforcer.

Figure 7 is a transverse detail section taken on line VII—VII of Figure 6.

As shown on the drawings:

In the form of the device illustrated in Figures 1, 2, and 3, the reference numeral 1 indicates a road subgrade upon which the upper or crown portion of a road is supported and formed between side road forms 2. The upper or crown portion of the concrete road is formed by dividing the same into a plurality of concrete sections or slabs 3. The slabs 3 are formed by means of transversely disposed expansion joints 4 and contraction joints 5 which are located at spaced in-

45

50

55

5 intervals between the expansion joint 4 as clearly illustrated in Figure 1. To complete the forming of the road slabs a center joint is provided longitudinally along the middle of the top or crown section of the road.

10 The center joint herein illustrated and described is of the type covered in my pending application for patent for a "Load transmission center joint" filed October 12, 1934, U. S. Serial No. 748,040.

15 The load transmission center joint used in the road construction comprises a T bar consisting of a base member or bottom plate 6 provided with rounded corners at 7 where it integrally connects up with an upwardly projecting flange or web 8. The flange 8 is provided with vertical cuts or slots at spaced intervals which extend downwardly from the top edge of the web to the base plate 6 to divide the web into a plurality of web sections each of which has struck outwardly from the upper margin thereof one or more anchoring plates or lugs 9 leaving one side of each of the web sections flat. The top surfaces of the base portion 6 of the load transmission base unit are 20 inclined downwardly toward the side margins of the base unit and as hereinbefore stated are provided with the curved corners 7 so that after the concrete has been poured to form the road slabs 3, said slabs may readily move away from and toward the base unit with the contraction and expansion of the road slabs. If desired the inclined top surfaces of the base section may be provided with a coating of grease or the like to eliminate any possibility of the concrete road slabs from 25 sticking to the base unit. The anchoring blades or lugs 9 of adjacent web sections project in opposite directions so that the anchoring blades of the base units are staggered with respect to one another.

30 Rigidly secured by brazing or other suitable means to each of the web sections 8 is the lower end of a supporting bar or post 10. The supporting bars 10 are secured on the sides of the web plate 8 from which the anchoring blades 9 project. Supported upon the upper ends of the bars or posts 10 is an upper joint sealer or center line T bar consisting of a top plate 12 and a depending flange or web 13. The top plate 12 is provided with inclined and rounded bottom surfaces 14, after 35 forming rounded corners where the plates 12 integrally connect up with the web 13. If desired the curved surfaces and rounded corners 14 of the upper joint sealer may be covered with a coat of grease or the like to obviate any sticking of the concrete slabs to the upper joint sealer when movement of the slabs takes place due to temperature changes. The top plate 12 serves as a center joint marking strip and a sealer for the top of the center joint crack. The depending flange or web 13 of the T bar unit has the marginal portion thereof cut and portions of said margin are deflected outwardly on one side only of the web to provide anchoring blades or wings 15. The anchoring blades 15 serve to hold the top sealer bar anchored in position against removal. The web or flange 8 of the base load transmission unit and the depending web 13 of the top sealer unit are positioned in substantially the same vertical plane and cause the concrete to crack in substantially the longitudinal center of the concrete road.

40 Attention is called to the fact that in the road construction described, the road slabs 3 have the bottom and upper edges of the inner and two side walls reenforced or protected by members of the various road joint forming mechanisms which

divide the crown or top portion of the road into slabs as illustrated in Figure 1.

45 For the purpose of protecting the lower outer edge of each of the road slabs 3 to obviate crumbling or cracking away of the same, particularly in cases where the shoulder of the road is formed of loose material, a road slab reenforcing unit is placed in position upon the road subgrade 1, before the pouring of concrete, and against the inner side of the road form 2. The reenforcing unit comprises an angle bar consisting of a bottom flange 16 and an upright flange 17 positioned at substantially right angles to the bottom flange. The upright flange 17 has struck therefrom anchoring blades or wings 18 which project from 50 the inner side of the flange 17 only and serve as a means for securely anchoring the reenforcing bar to the slabs with the outer surfaces of the base flange 16 and the upright flange 17 serving as a protection for the lower corner of 55 the slabs after the road form 2 is removed. Pins or stakes 19 are driven into the subgrade 1 to contact with the inner edges of the base flange 16, before the pouring of concrete, to hold the reenforcing unit in position against the side 60 form 2.

65 Figures 4 and 5 illustrate a modified form of a road slab reenforcing unit for the protection of both the bottom and upper edges of the outer wall of a concrete road slab 3. In this form of 30 the slab reenforcer unit the bottom reenforcer is constructed substantially the same as that illustrated and described in connection with Figure 2 and is numbered accordingly. Brazed or otherwise rigidly secured to the inner face of 35 the upright flange 17 of the base reenforcer are a plurality of posts or bars 20. Brazed or otherwise rigidly secured to the upper end of the supporting bars 20 is an upper edge reenforcing unit constructed identical to the lower edge re- 40 enforcing unit except that it is inverted as clearly illustrated in Figure 4. As clearly illustrated in Figure 5 the anchoring blades 18 of the upper reenforcing unit are staggered with respect to the anchoring blades 18 of the lower reenforcing unit. With the edge reenforcing units mounted in position against the inner side of the side road form 2 concrete is poured to form the road slab 3. After the concrete has been sufficiently cured the side form 2 is removed and the ma- 50 terial for forming the shoulder of the road is put in place. It will be noted that the reenforcing units protect the bottom and top edges of the outer wall of the road slab 3 and will obviate breaking away of the edges or undue cracking if 55 the shoulder of the road is not sufficiently strong to protect the outer side walls of the concrete road.

60 Figures 6 and 7 illustrate another modified form of a concrete road slab edge reenforcer adapted to be imbedded in any of the edges of the concrete slab and preferably in either the bottom outer edge or in both the bottom outer edge and the top outer edges similar to the arrangement illustrated in Figures 2 and 4 of the 65 drawings.

65 The modified form of slab edge reenforcer comprises an angle bar consisting of a base flange 21 and an upright flange 22 integrally formed at substantially right angles to the base flange. The upper margin of the upright flange 22 is deflected inwardly to form a top flange or bead 23 which serves to strengthen or reenforce the upper margin of the upright flange 22. Struck inwardly from the upright flange 22, between the upper 70 75

and lower margins thereof are a plurality of spaced anchoring blades or wings 24 which are bent along an inclined edge 25 thereby causing the anchoring blades 24 to assume an upwardly inclined position to project above the reenforcing or top flange 23 as clearly illustrated in Figure 7.

It will of course be understood that various details of construction may be varied through a wide range without departing from the principles 10 of this invention and it is therefore not the purpose to limit the patent granted hereon otherwise than necessitated by the scope of the appended claim.

I claim as my invention:

A concrete road construction comprising a concrete body, a load transmission center joint forming unit imbedded therein including a load transmission base, a top sealer, staggered uprights for connecting the load transmission base and said top sealer, reenforcing means imbedded in the upper and lower outer edges of the concrete road to reinforce and protect the outer edges against breakage, and uprights for supporting the upper 10 reenforcing means on the lower reenforcing means.

ROBERT R. ROBERTSON.
